ELEMIR J. NEY, OF DRACUT, MASSACHUSETTS, ASSIGNOR TO HARTFORD CARPET COMPANY, OF HARTFORD, CONNECTICUT.

Design No. 5,000, dated June 13, 1871.

DESIGN FOR A CARPET-PATTERN.

The Schedule referred to in these Letters Patent and making part of the same.

To all whom it may concern:

Be it known that I, ELEMIR J. NEY, of Dracut, county of Middlesex, State of Massachusetts, have invented or produced a new and original Design for a Pattern to be inwrought into Ingrain and other Carpeting in colors similar to those painted on the drawings or photographs accompanying this specification, or in colors substituted in the place of those painted on the drawings or photographs herewith; and I do hereby declare that the drawings accompanying this specification do give and convey, to any one skilled in the art of carpet-weaving, a defined and thorough description of the nature of my invention, and are sufficient to enable any one skilled in the art of carpet-weaving to use my invention.

What I claim as my invention, and desire to secure by Letters Patent, is—

The configuration of the design hereunto annexed, when applied to carpeting in the form similar to the drawings or photographs accompanying this specification.

E. J. NEY.
